UNITED STATES PATENT OFFICE.

EDWARD E. HINRICHSEN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,271,897.

Specification of Letters Patent.

Patented July 9, 1918.

Application filed February 20, 1917. Serial No. 149,745.

To all whom it may concern:

Be it known that I, EDWARD E. HINRICHSEN, a citizen of the United States, residing at New York, in the county of New York 5 and State of New York, have invented certain new and useful Improvements in Telephone-Exchange Systems, of which the following is a full, clear, concise, and exact description.

10 This invention relates to telephone exchange systems of the central office type, its object being the production of improved signaling means in such systems.

In accordance with a feature of this 15 invention, a sleeve relay associated with one end of the link circuit coöperates with the supervisory relay and a locking relay to control the intermittent operation of the signaling device.

20 In accordance with another feature of this invention, a differentially wound listening relay, controlling the connection of the operator's telephone set to the cord circuit, has its operating winding in circuit with the 25 supervisory signaling device, and the resistance which forms a shunt for the supervisory signaling device is wound on the differential relay in the form of a compensating winding.

30 This invention is illustrated in the accompanying drawings in which all apparatus is shown in its normal and unactuated condition.

There is shown in the drawing a telephone exchange system containing one embodiment of this invention and comprising subscribers' lines A and B, terminating at a central office, and a cord circuit C thereat for connecting the subscribers' lines. It will 35 be understood that a plurality of lines, similar to A and B, terminate at the central office, but, for the sake of simplicity, only the two lines are shown. It is believed that the invention will be fully understood from a 40 description of the operation of the system shown in the drawing, and it will be so described.

Assuming that subscriber A desires to be 45 connected with subscriber B, A will signal the central office in the usual manner, whereupon the operator inserts the answering plug of the cord circuit C into the jack associated with line A. Cut-off relay 5, listening relay 6 and supervisory relay 7 thereupon operate.

The operating circuit for relays 5 and 6 may 55 be traced from battery through answering supervisory lamp 8, operating winding 9 of relay 6, sleeve contacts of the answering plug and jack and the winding of cut-off relay 5 to ground. The operation of relay 6 connects the operator's telephone set to the cord 60 circuit, and completes an operating circuit for relay 10 through the lower winding thereof. Relay 10, in operating, completes a locking circuit for itself from battery 65 through contact 11 of relay 10, contact of supervisory relay 7, contact 12 of relay 10, upper winding thereof, windings 15 and 9 of relay 6, and sleeve contacts of the answering plug and jack, and the winding of relay 5 70 to ground. The upper winding of relay 10 and winding 15 of relay 6 are of low resistance and form a shunt for answering supervisory lamp 8, thereby preventing the lighting thereof. Upon the shunt circuit for 75 lamp 8 being established, there is an increased flow of current through winding 9 of relay 6, and the connections of winding 15 of relay 6 are such that this winding serves to compensate for this increased flow 80 of current through winding 9, with the result that the net energization of the relay 6 is not increased after the establishment of the shunt circuit for lamp 8.

Upon being advised that subscriber A desires to be connected to the line of subscriber B, the operator inserts the calling plug of the cord circuit C into the jack of line B, whereupon the calling sleeve relay 20 and cut-off relay 21 operate, and calling supervisory lamp 23 is lighted. Upon the operation of calling sleeve relay 20, a circuit is completed through winding 22 of relay 6. The direction of flow of current through windings 9 and 22 of relay 6 is opposite, so 95 that, upon the establishment of the circuit through winding 22, relay 6 releases, disconnecting the operator's telephone set from the cord circuit, and opening the operating circuit through the lower winding of relay 10. The operator may signal subscriber B 100 in any desired manner. Subscriber B, in responding, removes the receiver from the switchhook and causes the operation of calling supervisory relay 24, which closes a 105 shunt circuit containing a resistance 25 about the calling supervisory lamp 23, which is thereupon effaced.

The subscribers, upon finishing conversation, restore their receivers to the switchhooks, whereupon supervisory relays 7 and 24 release. The release of relay 24 causes 5 calling supervisory lamp 23 to light to furnish a disconnect signal. The release of the answering supervisory relay 7 opens the locking circuit through relay 10, whereupon this relay releases, connecting interrupter 10 26 to the armature of answering supervisory relay 7. The release of relay 7 also removes the shunt from about supervisory lamp 8, whereupon this lamp lights to furnish a disconnect signal. The operator may then 15 withdraw the plugs from the jacks, whereupon all apparatus returns to normal.

Suppose, however, that before the plugs are withdrawn from the jacks, subscriber A should desire to make a recall, then the removal of the receiver from the switchhook by subscriber A causes the intermittent operation of the supervisory lamp 8 to furnish a recall signal to the operator. This is accomplished in the following manner: The 20 removal of the receiver from the switchhook by subscriber A causes the operation of supervisory relay 7, which connects the interrupter 26 in circuit with resistance 27, the compensating winding 15 and operating winding 9 of relay 6, sleeve contacts of answering plug and jack, and the winding of cut-off relay to ground. The resistance 27 has the same value as the upper winding 25 of relay 10, and with compensating winding 15 forms a shunt for answering supervisory lamp 8. It will be seen, therefore, that in the operation of interrupter 26, this shunt, comprising the resistance 27 and compensating winding 15, is intermittently placed 30 about the lamp 8, whereby this lamp is intermittently operated to furnish a recall signal to the operator. The operator, upon observing the intermittent operation of the answering supervisory lamp 8, will actuate 35 key 28, whereupon the neutralizing winding 22 of relay 6 will be short-circuited by direct battery through normal contact of calling supervisory relay 24. Relay 6 thereupon attracts its armatures, connecting the operator's telephone set to the cord circuit, and causing the operation of relay 10, which 40 immediately establishes a locking circuit for itself as hereinbefore traced. The operator, upon being advised of the number of the subscriber desired, withdraws the calling plug 45 from the jack line B, restores key 28 to normal position, and completes the connection with the desired subscriber in the manner hereinbefore described.

60 What is claimed is:

1. A telephone exchange system comprising telephone lines, a link circuit for interconnecting the lines, a supervisory relay and a second relay operating upon the connection of the link circuit with a calling line,

a third relay actuated upon the operation of the second relay, a locking circuit for the third relay including a winding of the second relay established upon the operation of the second relay and the supervisory relay, 70 a signaling device, and a source of intermittent current brought into circuit with the signaling device upon the subsequent deenergization of the third relay and the energization of the supervisory relay. 75

2. A telephone exchange system comprising telephone lines, a link circuit for interconnecting the lines, a supervisory relay and a second relay energized upon the connection of the link circuit with a calling line, a third relay actuated upon the energization of the second relay, a locking circuit for the third relay established upon the actuation thereof for rendering this relay independent of the second relay, a signaling device, and a source of intermittent current brought into circuit with the signaling device by the subsequent deenergization of the third relay followed by the energization of the supervisory relay. 80

3. A telephone exchange system comprising telephone lines, a link circuit for interconnecting the lines, a supervisory relay and a listening relay operating upon the connection of the link circuit with a calling line, an operator's telephone set connected with the link circuit upon the operation of the listening relay, a third relay actuated upon the operation of the listening relay, a locking circuit for the third relay including a winding of the listening relay established 90 upon the operation of the third relay and the supervisory relay, a signaling device, and a source of intermittent current brought into circuit with the signaling device upon the subsequent deenergization of the third relay and the operation of the supervisory relay. 100

4. A telephone exchange system comprising telephone lines, a link circuit for interconnecting the lines, a supervisory relay and a listening relay operated upon the connection of the link circuit with a calling line, an operator's telephone set connected with the link circuit upon the operation of the listening relay, a third relay actuated upon 110 the operation of the listening relay, a locking circuit for the third relay established upon the operation thereof for rendering this relay independent of the listening relay, a signaling device, and a source of intermittent current brought into circuit with the signaling device by the subsequent deenergization of the third relay followed by the energization of the supervisory relay. 115

5. A telephone exchange system comprising telephone lines, a link circuit, an operator's telephone set, a listening relay controlling the connection of the operator's telephone set to the link circuit, a supervisory relay, a third relay, an energizing cir- 125 130

cuit therefor established upon the energization of the listening relay, a signaling device, interrupter mechanism, and a circuit including the signaling device, a winding of the listening relay and the interrupter mechanism established by the subsequent de-energization of the third relay followed by the energization of the supervisory relay.

6. A telephone exchange system comprising telephone lines, a link circuit, an operator's telephone set, a listening relay controlling the connection of the operator's telephone set to the link circuit, a supervisory relay, a third relay actuated upon the energization of the listening relay, a locking circuit therefor including a winding of the listening relay established upon the operation of the third relay and the supervisory relay, a signaling device and interrupter mechanism, and a circuit therefor open at two points, the circuit being closed at one point by the subsequent de-energization of the third relay upon the release of the supervisory relay, and at the other point by the subsequent energization of the super-

visory relay to cause the intermittent operation of the signaling device.

7. A telephone exchange system comprising telephone lines, a link circuit for interconnecting the lines, a listening relay having an operating, a compensating and a neutralizing winding, a signaling device, a circuit including the operating winding of the listening relay and the signaling device established upon connection of one end of the link circuit with a line, an operator's telephone set controlled by the listening relay, a supervisory relay, a shunt circuit comprising the compensating winding of the listening relay connected about the signaling device upon the energization of the supervisory relay, and a circuit including the neutralizing winding of the listening relay completed upon the connection of the other end of the link circuit with another line. 45

In witness whereof, I hereunto subscribe my name this 19th day of February, A. D. 1917.

EDWARD E. HINRICHSEN.
